UNITED STATES PATENT OFFICE.

SAMUEL C. PERRY, OF LONDON, KENTUCKY.

AUTOMATIC SIGNAL SYSTEM FOR RAILWAYS.

1,025,018.

Specification of Letters Patent. Patented Apr. 30, 1912.

Application filed October 18, 1911. Serial No. 655,445.

To all whom it may concern:

Be it known that I, SAMUEL C. PERRY, a citizen of the United States, residing at London, in the county of Laurel and State 5 of Kentucky, have invented a new and useful Automatic Signal System for Railways; and I do hereby declare the following to be a full, clear, and exact description of the invention, such as will enable others skilled 10 in the art to which it appertains to make and use the same.

This invention relates to a new and useful automatic mechanical inter-lock signal system, adapted mainly for use on railways, 15 which comprises a track running north and south, which is crossed approximately at right angles thereto by an east and west track; this system is applicable to double tracks running in the same directions, with 20 the exception that various parts are to be duplicated, in order to attain the desired result. The system may also be applied to a single track running in any desired direction.

25 The invention in its broadest scope aims as its primary object to provide means adjacent each track to be operated by the flanges of the engine's wheels, so as to throw the signals on the intersecting track.

30 A further object of the invention is to provide automatic means for locking the signals in the positions in which they are thrown, and after the train, if south bound has passed the crossing, means are provided 35 to be actuated by the wheel's flanges, to unlock the signals, thereby permitting them to be returned to their normal position.

One of the features of the invention is the provision of a bar having a universal 40 connection at its stationary point between the rails, so as to permit the bar to be separated from one of the rails, when operating one set of signals, and to be pressed downwardly by the flanges of the wheels, after 45 the train has passed the crossing, and is continuing on its way.

A further feature of the invention is the provision of a plurality of bell crank levers, so connected with the signal mechanisms of 50 the east and west north and south intersecting tracks, so that the signals on the east and west track will be thrown at danger, when a train bound south or north is approaching the crossing or the intersecting 55 of the tracks.

The invention comprises further features

and combination of parts, as hereinafter set forth, shown in the drawings and claimed.

In the drawings:—Figure 1 is a plan view of a railroad crossing, showing the improved automatic mechanical inter-lock signal system as applied thereto, the same being constructed in accordance with the invention. Fig. 2 is a detail perspective view, showing how one of the bell crank levers is 60 locked, which holds the signals at danger until the train has entirely passed the crossing, after which the locking mechanism is unlocked. Fig. 3 is a detail perspective view of the bar, which is operated by the 65 flanges of the wheels, which bar is provided with a universal connection to a stationary point. Fig. 4 is a sectional view on line 70 4—4 of Fig. 3. Fig. 5 is a sectional view on line 5—5 of Fig. 3.

Referring more especially to the drawings 75 1 designates the tracks or rails running north and south, which intersect or cross the rails 2 running east and west. The crossing of the rails is indicated by the 80 numeral 3. The crossing is supported on the intersecting ties 4 and 5, in the ends of which bifurcations 6 are formed. Mounted in the arms formed by the bifurcations are pivot pins 7, on which the bell crank levers 85 8, 8^a, 9, 9^a, 10, 10^a, 11 and 11^a.

Arranged at *a* adjacent one of the rails, at each end of the north and south track is a signal throwing bar 12, while at the points *b* of the east and west track a similar bar 90 13 is disposed. These bars 12 and 13 at one end are provided with universal connections 14 to the raised portions 15, as shown, so as to permit the bars to be swung sidewise, or downwardly. Pivotaly mounted at 16 and 17 to the ties 18 and 19 are the bell crank levers 20 and 21, between each of which and each of the bars 12 rods 22 and 23 are connected. Pivotaly mounted on the ties 24 and 25 of the east and 100 west track are the bell crank levers 26 and 27. Connecting between each of the bell 105 crank levers 26 and 27 and each of the signal throwing bars 13 are rods 28 and 29. The bars 13 are also provided with universal connections 14 to the raised portions 15.

Mounted on the ties *c*, *d*, *e*, and *f* of the tracks running north and south east and west are frames 33, in which the signal 110 shafts 34 having cranks 35, 36, 37 and 38^a, are mounted. The upper ends of the shafts

are provided with the usual signal blades, 38, 39, 40 and 41. Springs 42 are connected between the cranks of the shafts 34, and one of the rail ties, so as to return the 5 signals to their normal position, after having been unlocked.

Connecting between one of the arms of the bell crank lever 20 and one of the arms of the bell crank lever 8^a is the cable 44, 10 while connecting between the crank 35 and the bell crank lever 8 is a cable 45. A cable 46 is connected between the bell crank levers 27 and 9^a. A cable 47 is connected between the arms of the bell crank levers 8^a 15 and 9, while a cable 48 connects between the bell crank lever 8 and the bell crank lever 11. The lever 11 is in turn connected to the crank 38^a by virtue of the cable 49. The cables 50 and 51 are connected between 20 one of the arms of each of the levers 10 and 11^a, and 11 and 10^a, while a cable 52 connects between one arm of each of the bell crank levers 9^a and 10. A cable 53 connects between the bell crank lever 9 and the bell crank lever 10^a, while the cable 54 is 25 connected between the bell crank levers 8 and 11^a. Connecting between the bell crank levers 8 and 9^a is a cable 55. The cranks 36, and 37, are each connected to one of 30 the arms of each of the bell crank levers 9, and 10, by means of the cables 56 and 57. A cable 58 connects the bell crank lever 21 and the bell crank lever 10^a, while a similar cable 59 connects between the bell crank 35 lever 26 and the bell crank lever 11^a. Mov- 40 able with each of the bell crank levers 8^a, 9^a, 10^a, and 11^a are the usual form of signals 60, which indicates to the engineer on any train running east or west, or north or south that, the signals on the track running at right angles have been operated.

Projecting from the tie 5 is a frame 61, having a bell crank lever 62 pivoted therein as at 63, one end of which bell crank lever 45 engages beneath the bell crank lever 10^a there being a spring 64 holding this bell crank lever 62 normally against the underneath side of the lever 10^a. However, just so soon as the bell crank lever 21 is rocked 50 on its pivot by the signal throwing bar 12, thus actuating the bell crank lever 10^a in the direction of the arrow 65, the arm 62^a of the bell crank lever 62 is thrown in the path of the lever 10^a, thus locking the sig- 55 nals of the east and west track at danger. After the train bound south has passed the crossing 3, the bell crank lever 62 is thrown from the path of the bell crank lever 10^a, by means of the bar 67, being actuated by 60 the flanges of the wheels. This bar 67 to operate the bell crank lever 62 is provided with connections 68, 69 and 70 therewith. When the bell crank lever 62 is thrown from the path of the lever 10^a, the signals of the 65 east and west track are returned to their

normal position, which is clear. This lock and release mechanism for the signals may be equipped on each side of the crossing on each north and south, east and west tracks, if desired, so that trains running 70 either north or south, east or west may lock the signals and then release them.

A train bound south will throw the signals on the east and west tracks, by actuating one of the bars 12, which in turn actuate the bell crank levers 9, 10^a and 11. 75 When a train is passing the crossing bound north the signals of the east and west track are thrown at danger, by the actuation of the other bars 12, which in turn actuate 80 the bell crank levers 20, 8^a, 9, and 11. A train bound west will throw the signals of the north and south track at danger by actuating one of the bars 13, which in turn oscillate the bell crank levers 26, 11^a, 8, and 85 10, while a train bound east will throw the signals of the north and south track at danger by operating the other bar 13, thus in turn actuating the bell crank levers 27, 9^a, 10 and 8. 90

The invention having been set forth, what is claimed as new and useful is:—

1. In a signal system as set forth, railway tracks intersecting at right angles to one another, signals arranged adjacent each 95 track on each side of the intersection, means arranged adjacent each track in advance of the intersection thereof adapted to be operated by the flanges of the wheels for throwing the signals of the track running 100 at right angles at danger, and connections between the means of each track and the signals of the track running at right angles, said means having a universal connection at one end with one of the rail ties, so as 105 to permit it to be moved laterally of the rail or downwardly thereof.

2. In a signal system as set forth, railway tracks intersecting at right angles to one another, signals arranged adjacent each 110 track on each side of the intersection, means arranged adjacent each track in advance of the intersection thereof adapted to be operated by the flanges of the wheels for throwing the signals of the track running 115 at right angles at danger, and connections between the means of each track and the signals of the track running at right angles, and means coöperating with the connections, for locking the signals. 120

3. In a signal system as set forth, railway tracks intersecting at right angles to one another, signals arranged adjacent each track on each side of the intersection, means arranged adjacent each track in advance of 125 the intersection thereof adapted to be operated by the flanges of the wheels for throwing the signals of the track running at right angles at danger, and connections between the means of each track and the 130

signals of the track running at right angles, and means coöperating with the connections, for locking the signals, and means actuated by the flanges of the car wheels 5 for releasing the locking means.

4. In a signal system as set forth, railway tracks intersecting at right angles to one another, signals arranged adjacent each track on each side of the intersection, means 10 arranged adjacent each track in advance of the intersection thereof adapted to be operated by the flanges of the wheels for throwing the signals of the track running at right angles at danger, and connections 15 between the means of each track and the signals of the track running at right angles,

said means having a universal connection at one end with one of the rail ties, so as to permit it to be moved laterally of the rail or downwardly thereof, means coöoperative 20 with the connections, for locking the signals, and means actuated by the flanges of the car wheels for releasing the locking means.

In testimony whereof I have signed my 25 name to this specification in the presence of two subscribing witnesses.
